UNITED STATES PATENT OFFICE

150,154

DESIGN FOR A MACHINE FOR VENDING
CIGARETTES OR THE LIKE

Fred L. Meagher, Syosset, N. Y., assignor to Mills
Industries, Incorporated, Chicago, Ill., a corporation of Illinois

Application March 9, 1946, Serial No. 127,303

Term of patent 7 years

(Cl. D52—3)

To all whom it may concern:

Be it known that I, Fred L. Meagher, a citizen of the United States of America, residing at Syosset, in the county of Nassau and State of New York, have invented a new, original, and ornamental Design for Machine for Vending Cigarettes or the like, of which the following is a specification, reference being had to the accompanying drawing, forming a part thereof.

The single figure of the drawing is a prospective view of a machine for vending cigarettes or the like showing my new design.

The rear of the vending machine is plain and the side not disclosed is the same as the side shown.

I claim:

The ornamental design for a machine for vending cigarettes or the like, as shown and described.

FRED L. MEAGHER.
